CLOSURE FOR MANHOLES, WATER METER HOLES, AND THE LIKE

Filed Sept. 1, 1925

Inventor
Conrad Ehret

BY Loyal J. Miller

ATTORNEY.

UNITED STATES PATENT OFFICE.

CONRAD EHRET, OF OKLAHOMA CITY, OKLAHOMA.

CLOSURE FOR MANHOLES, WATER-METER HOLES, AND THE LIKE.

Application filed September 1, 1925. Serial No. 53,809.

My invention pertains to closures for man-holes, water-meter holes, and the like.

The object of my invention is to provide a device of the character described which 5 will be cheaply, easily and economically made, easily applied, easily fastened and unfastened, permanently locked when the key is withdrawn; one which will be secure against opening except with the use of the 10 key, which cannot be unlocked without the key; it prevents the turning over of the covers or closures for man-holes water-meter holes, and the like, and the dangers incident to such turning over; it prevents the tampering 15 with the meters by any person except those having the use of the key.

The invention, novel features, details of construction, combination of parts, and other objects of the invention, will be hereinafter more particularly set forth, illustrated in the accompanying one-sheet drawing, and pointed out in the appended claim.

Reference is hereby made to the drawing forming a part of this application, of which, 20 Figure 1 is a plan view of the device, inverted.

Figure 2 is a plan view of a portion of the device, in section, on the line A—A of Figure 1.

Figure 3 is a plan view of the exterior of the device.

Like characters of reference designate like parts in all the figures.

The device consists of a heavy circularly shaped outer flat ring member, 1, with a sunken curved portion 2, 3, lower than its outer flat portion, four downwardly extending lugs on its under side 4, 5, 6 and 7, each having a perforation near its lower part at 35 right angles to the inside centre of said flat ring member, for the more easy handling of said flat ring member. Said flat ring member 1 is seated in the outer portion of the man-hole, water-meter hole, or the like.

A second member 8 of said device is principally a plane surface and is circularly shaped, its outer periphery is beveled 9, 30, and is seated in the sunken curved portion of said member 1 at 2 and 3. Said member 40 8 has two downwardly extending lugs 13 14 on its lower surface placed thereon opposite a tongue member 21, said lugs curved outwardly and forming a bearing or hinge on which to raise said member 8 when said 45 tongue member 21 is released and said member 8 is raised upwardly from its seat at said

tongue member, thereby resting on said lugs 13 and 14. Centrally of said member 8 on its under surface at right angles to said tongue member 21 is a downwardly extending perpendicular brace or arm 17 having two cross-section supporting braces or arms 15, 16, at right angles to said arm or brace 17. Said brace 17 is centrally perforated as at 18 in which perforation rides a bolt 65 19 forming a part of said tongue member 21; the flat surface portion of said tongue member 21 rides on a downwardly extending lug 29 on the under surface of said member 8 made integrally therewith. Said 70 tongue member 21 has an elongated perforated slot 23 near its outer surface 24, through which slot 23 is an upstanding bolt 25 rigidly fastened to said member 8. A washer 27 is loosely placed over said member 75 21 on said bolt 25 and held in place thereon by a nut 26, to assist said tongue member 21 to operate slidably through said perforation 18 on bolt 19 and lug 29. A suitable coil spring 20 is placed on said bolt 19 80 between brace 17 and the shoulders on said tongue member 21 where said bolt 19 ends integral with said tongue member 21. Said tongue member 21 has a groove 22 on one side adjacent semi-circular lug 28. In the 85 under side of said member 8 and integral therewith and opposite said groove 22 is a downwardly extending semi-circular lug 28 the inner bore of which is integral with and a continuation of the round lobe 10 of the 90 key-hole through the top of said member 8, said semi-circular lug 28 being open for the other two portions of the key-hole 11 and 12. In operation: When flat ring member 1 is securely placed on the outer portion of the 95 man-hole, water-meter hole, or the like, the second member 8 is placed on the inner edges 2, 3 of member 1, with lugs 13 and 14 under said curved portion 2, 3; the key, which is a standard key of the man-hole, water-meter 100 hole, and the like, is inserted in the key-hole 10, 11 and 12, and the key turned, the circular lobe 10 thereof being held tight by the semi-circular open lug 28, the portions 11 and 12 of said key being in operative position with the groove 22 of said tongue member 21, when the key is turned the portions of the key corresponding in shape to the key-hole 11 and 12 presses against the inner edge of the groove 22, and forces the tongue 110 member 21 away from its seat, tightens the spring 20 around the bolt 19, forces said bolt

19 further into said perforation 18 in brace 17, by slidably operating said tongue member 21 on lug 29, bolt 19 and bolt 25 and release beveled portion 24 of said tongue member from operative locking position with the under side of curved portion 2, 3 of said member 1. By then pulling, or prying on the key, the member 8 is raised, or entirely removed if desired. When it is again desired to be placed in position for safety, this process can be reversed, or gone over again, and the closure again placed in its securely tight, and locked-in position.

It will be observed whenever the key is removed whether the closure is in place or removed the spring 20 then automatically forces the tongue member forward along the line of the elongated slot 23 so that bolt 25 is at the innermost point of the throw of said slot 23, and when it is seated, throws the bevelled bolt 24 forward and under said ledge of the curved portions 2, 3 of member 1; when not seated, it is impossible to replace the member 8 without the releasing of said tongue member; and when seated it is impossible to withdraw the key from the key-hole without locking the closure.

From the description of the one-sheet accompanying drawing and the specifications the advantages of the making, construction,

operation and applying of the device will be apparent to those skilled in the art to which my invention pertains; but it will be understood that any modifications within the scope of the claimed invention may be made in the construction, operation and application without departing from the principle of the invention, or sacrificing any of its advantages.

Having thus described the invention, what is claimed and desired to be secured by Letters Patent, is:

A closure for the purpose described, comprising a substantially flat ring member with sunken concave portion and lugs, a circular member having beveled periphery received in said sunken curved portion, curved lugs, bracing arms, and a transverse brace arm at right angles thereto, a tongue member, a slideable bolt movable with said tongue member and guided in said transverse brace, a spring interposed between the said transverse brace arm and the adjacent end of the tongue member, said bolt having a beveled end engaging the concave portion of the ring member, said tongue having a groove, and a semi circular lug on the circular member co-operating with said groove and with the key that actuates the said tongue member.

CON EHRET.
